UNITED STATES PATENT OFFICE.

CHARLES C. BLAKE, OF BROOKLINE, MASSACHUSETTS, ASSIGNOR TO C. C. BLAKE, INCORPORATED, OF BOSTON, MASSACHUSETTS, A CORPORATION OF NEW YORK.

SHOE.

Application filed February 9, 1921. Serial No. 443,581.

The present invention relates to shoes and more particularly to welt shoes.

The object of the invention is to improve the construction of welt shoes particularly with respect to the insole and the manner in which the upper is lasted and the welt secured thereto.

In the drawings which illustrate the preferred embodiment of the invention,

10 Figure 1 is a plan of the insole;

Fig. 2 is a sectional elevation of a welt shoe having the insole shown in Fig. 1 incorporated therein;

15 Fig. 3 is a sectional elevation of the reinforced body portion having its edge upturned to form a peripheral wall;

Fig. 4 is a plan of the apparatus for forming the insole;

20 Fig. 5 is a plan of the formed insole in its mold;

Fig. 6 is a sectional elevation on the line 6-6, Fig. 5;

Fig. 7 is a sectional elevation on the line 7-7, Fig. 4; and

25 Fig. 8 is a plan of the metallic fastening used in the inseam.

Referring now to Fig. 2, the insole of the welt shoe comprises a body portion 1, having its extreme edge upturned to form a 30 vertical peripheral wall 2, and a sole-shaped blank 3 filling the cavity bounded by the peripheral wall.

In making the insole a sheet of split leather 4 (Fig. 7) reinforced with a sheet 35 of duck 5 is placed over a sole-shaped mold 6 having a lining 7 on its bottom. The body portion is pressed into the mold to upturn its extreme edge and form the vertical peripheral wall by a presser 8 (Figs. 4 and 7).

40 Thereafter the presser 8 is removed and a sole-shaped blank 9 composed of linoleum is assembled with the body portion to fill the cavity bounded by the peripheral wall. The excess material in the peripheral wall is 45 then trimmed flush with the surface of the blank 9. The formed insole is then removed from the mold by inserting suitable tools through holes 10 in the bottom of the mold 6 and punching the lining 7 and formed 50 insole out of the mold.

In making the shoe the formed insole is assembled with an upper 11 on a last (not shown) and then the upper is lasted to the outside face of the peripheral wall 2 in accordance with the method of lasting de-

scribed in Letters Patent No. 1,261,741, granted to me April 2, 1918. After the lasting operation the blank 3 is removed from the cavity bounded by the peripheral wall 2 to prepare the shoe for the weltting operation. In this operation the welt 12 is secured to the lasted shoe by metallic fastenings 13 (Fig. 8). These fastenings are bifurcated at each end and during the weltting operation they are inserted through the welt, upper, and insole, the bifurcations on one end being clenched in the base of the slit 14 in the welt and the bifurcations on the other end being clenched on the inside face of the peripheral wall 2. After the weltting operation the blank 3 is secured in place to fill the cavity bounded by the peripheral wall 2 and an outsole is secured to the welted shoe shown by the outseam 15.

What is claimed as new is:

1. As an article of manufacture an insole for a welt shoe comprising a sole-shaped body portion having its extreme edge upturned to form a vertical peripheral wall and a solid sole-shaped blank filling the cavity within the wall. 75

2. As an article of manufacture an insole for a welt shoe comprising a reinforced sole-shaped body portion having its extreme edge upturned to form a vertical peripheral wall and a solid sole-shaped blank filling the cavity within the wall. 85

3. A step product of the lasting operation having, in combination, an insole having its extreme edge upturned to form a vertical peripheral wall, an upper lasted to the outside face of the wall and a sole-shaped blank filling the cavity within the wall. 90

4. A welted shoe, having, in combination, an insole having its extreme edge upturned to form a vertical peripheral wall, an upper lasted to the insole, and a welt secured to the upper and insole by metallic fastenings anchored entirely within the welt and on the inside face of the wall. 100

5. A welted shoe, having, in combination, an insole having its edge upturned to form a peripheral wall, an upper lasted to the insole, and a welt secured to the upper and insole by metallic fastenings both ends of 105 which are bifurcated, the bifurcations of one end being clenched in the welt and the bifurcations of the other end being clenched on the inside face of the wall.

6. A welted shoe, having, in combination,

an insole having its edge upturned to form a peripheral wall, an upper lasted to the outside face of the wall, and a welt provided with a longitudinal slit secured to the upper and insole by metallic fastenings both ends of which are bifurcated, the bifurcations of one end being clenched in the base of the slit in the welt and the bifurcations of the other end being clenched on the inside face of the wall.

7. That improvement in the art of making insoles as an article of manufacture for welt shoes which consists in upturning the extreme edge of a sheet of material to form a vertical peripheral wall therefrom and pressing a solid sole-shaped blank within the wall to fill the cavity bounded thereby.

8. That improvement in the art of making insoles as an article of manufacture for welt shoes which consists in pressing a sheet of material into a mold having a sole-shaped cavity therein to upturn the edge of the body portion and thus form a peripheral wall therefrom, pressing a solid sole-shaped blank within the wall, and trimming the

wall substantially flush with the surface of the blank.

9. That improvement in the art of making shoes which consists in upturning the edge of a sheet of material to form a peripheral wall therefrom, pressing a sole-shaped blank within the wall to fill the cavity bounded thereby, assembling the insole thus formed with an upper on a last, lasting the upper to the outside edge face of the wall, removing the blank from the insole, securing a welt to the upper and insole, reinserting the blank, and finishing the shoe.

10. A welted shoe, having, in combination, an insole having its extreme edge upturned to form a vertical peripheral wall, an upper lasted to the outside face of the wall, and a welt secured to the upper and insole by a metallic fastening inseam anchored entirely within the body portion of the welt and upon the inside face of the wall.

In testimony whereof I have signed my name to this specification.

CHARLES C. BLAKE.
